UNITED STATES PATENT OFFICE

GUSTAV C. PAHLOW, OF GALESBURG, ILLINOIS

DESIGN FOR A CASKET LUG

Application filed July 1, 1929. Serial No. 31,898. Term of patent 7 years.

To all whom it may concern:

Be it known that I, GUSTAV C. PAHLOW, a citizen of the United States, residing at Galesburg, in the county of Knox and State of Illinois, have invented a new, original, and ornamental Design for a Casket Lug, of which the following is a specification, reference being had to the accompanying drawing, forming part thereof.

I claim:

The ornamental design for a casket lug, as shown.

GUSTAV C. PAHLOW,
